DESIGN FOR A JACKET

Nathan H. Sachs, Newton Center, Mass.

Application July 12, 1944, Serial No. 114,380

Term of patent 3½ years

(Cl. D3—4)

To all whom it may concern:

Be it known that I, Nathan H. Sachs, a citizen of the United States of America, residing in Newton Center, county of Middlesex, and State of Massachusetts, have invented a new, original, and ornamental Design for a Jacket, of which the following is a specification, reference being had to the accompanying drawing, forming part thereof.

Fig. 1 is a front view of a jacket showing my new design.

Fig. 2 is a rear view thereof.

I claim:

The ornamental design for a jacket, substantially as shown.

NATHAN H. SACHS.
